TRUCK-MOUNTED LOAD PUSHER AND
PULLER

Bronislaus I. Ulinski, Chicago, Ill., assignor to
The Yale & Towne Manufacturing Company,
Stamford, Conn., a corporation of Connecticut

Application January 18, 1949, Serial No. 71,500

17 Claims. (Cl. 214—514)

1

This invention relates to an attachment preferably adapted to be applied to an industrial lift truck, but adapted also to be embodied as an integral part thereof. More particularly, my invention relates to an attachment for a lift truck adapted to push a load linearly off the load platform of a truck of the particular class. A further portion of my invention relates to means adapted to pull a load onto the platform of the truck, so that in effect, my invention may be utilized for both pushing and pulling a load or for pushing only.

As a feature of my invention, my attachment is readily applied to any usual type of truck. As a further feature, when so applied, the attachment may be readily connected for immediate operation.

Load pushers and pullers are old and well known in the art. However, they are generally quite bulky, inefficient and expensive, and have not therefore been generally accepted for material handling. As a particular feature of my invention whereby it is rendered desirable and effective, my attachment is arranged to occupy an exceedingly small space so as not to increase the overall length of the truck. In addition, the attachment is so formed that it is considerably narrower than any usual standard type of load platform so as not to increase the overall width of the truck.

A further feature of my invention resides in the extremely novel concept of means carried by the attachment and connected respectively to what I term a load actuator and a part of the truck, for operation by a ram assembly to move the load actuator to and from the main frame of the truck. A particular feature of this part of the invention resides in an extremely efficient arrangement of movement multiplying means whereby a relatively short throw achieved by the ram assembly will effect a long throw of the load actuator and considerable linear movement of the load moved by the actuator.

A still further feature of my invention resides in the utilization of a load gripping assembly that may readily be applied to the load actuator of my invention so that the load actuator may become a load puller as well as a load pusher. As a particular feature of this part of the invention, the load gripper is adapted for movement to grip the load prior to movement of the actuator so that no special means must be manipulated by an operator to grip a load and then move it linearly. As a still further feature of this particular part of my invention, the load gripping means release the load at all times upon the stopping of the load moving operation.

2

Thus, the load is automatically released from its grippers whenever the pulling of the load is stopped by an operator. These automatic features I believe to be of great value in yielding a simple operating structure.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is a view of one end of an industrial truck showing my invention applied thereto and forming a part thereof. Fig. 2 is an end elevation of the truck of Fig. 1. Fig. 3 is an exploded view of certain of the parts of the ram assembly of my invention. Fig. 4 is a view of the parts of the ram assembly after some movement of certain of the parts thereof from the position of Fig. 1. Fig. 5 is a section taken along lines 5—5 of Fig. 4. Fig. 6 is a section taken along lines 6—6 of Fig. 5. Fig. 7 is a view looking downwardly on the ram assembly and the parts actuated thereby when the load actuator has been fully extended relatively to the truck frame. Fig. 8 is an elevation showing the construction of the load actuator. Figs. 9 and 10 are sections taken along lines 9—9 of Fig. 8 showing the gripper mechanism in two positions. Fig. 11 is a section through the gripper operating hydraulic means. Fig. 12 is a schematic drawing of the hydraulic mechanism of my invention.

Referring now more particularly to the drawings, and more especially to Figs. 1 and 7, I show at 10 the primary uprights of a standard type of industrial truck, the secondary uprights being designated by reference numeral 11. The load wheels of the truck are shown at 12, and at 13 there is shown a load carriage mounted through upper and lower rollers 14 for vertical movement on the secondary uprights 11. The attachment of my invention is here shown as applied to the carriage 13. Of course, those skilled in the art will understand that my attachment may be applied to any part of the

main frame of an industrial truck and that it is herein shown as applied to the main frame carriage 13 because that is the preferred manner in which my invention will probably be used at the present time. It should further be understood that while I call my invention an attachment, it can actually be an integral part of the truck. Thus, the base member of my attachment is designated by reference numeral 15 as best seen in Fig. 4 and this base member 15 may be welded to part of the main frame of a truck or may be applied to the main frame carriage 13 by merely forming on the base member 15 a lip 16 adapted to coact with the end plate 13a of the carriage 13. The attachment thus is secured for movement with the carriage as a part thereof.

What I have heretofore termed the ram assembly of my invention, I designate by reference numeral 17, the said ram assembly being well illustrated in Figs. 1, 2, 4, 5, and 7. Ram assembly 17 may be formed of one or more castings, the upper casting being shown supporting thereon what I term a ram cylinder 18. Cylinder 18 has a shaft portion 19 held by a heavy nut 19a in fixed relation to the upper casting of ram assembly 17 as best seen in Fig. 5. A ram piston 20 is mounted for vertical movement relatively to the ram cylinder 18 and is threaded at 21 so as to be secured to a heavy lower casting 22 of the ram assembly best illustrated in perspective in Fig. 3. Casting 22 has secured thereto through suitable nuts 23 a pair of racks 24, each of which is formed with teeth on its forward and rear faces. Each rack 24 cooperates with four gear sectors, there being two upper gear sectors 25, 26 and two lower gear sectors 27 and 28 in engagement with the rack teeth.

The gear sectors are all similar in construction, and each gear sector is secured to a lever. Thus, gear sector 25 is secured to a lever 29, while gear sectors 26, 27, and 28 are secured respectively to levers 30, 31, and 32. Considering first lever 29, we find that it is bored at 33 for a bearing shaft 34 carried by the upper casting of the ram assembly 17 through the intermediary of a bearing sleeve 35. Between the lever 29 and the ram assembly 17 there is positioned the gear sector 25, this gear sector being bored at 36 for the bearing shaft 34. Gear sector 25 is further bored at 37 for a bolt 38, this bolt passing through a bore 39 in the lever 29. Bolt 38 is headed at one end to lie in a counter-bored portion of bore 37 and is threaded at its other end for a nut 40. It is obvious that the nut 40 and the bolt 38 thus secure the gear segment 25 to the lever 29 for integral rotation therewith on the bearing shaft 34, and relatively to the ram assembly 17.

All the remaining levers and gear segments are similarly secured to the ram assembly 17, except that the lower levers 31, 32 are in offset relation to the levers 29 and 33, even though the gear sectors 27, 28 are in substantial alignment with the upper gear sectors 25, 26. Thus, as is best seen in Fig. 5, lower lever 31 lies at the right of its particular gear sector 27 for rotation therewith relatively to the ram assembly 17. Because the lower lever 31 is so offset relatively to upper lever 29, the two levers can lie in substantial vertical alignment as shown in Fig. 1. At the same time, of course, upper lever 33 can lie in substantial vertical alignment with lower lever 32. It will be well at this point to indicate further that the mounting of the four levers 29-32 that I have thus described is duplicated at the right side of

the ram assembly pictured in Fig. 5, there being thus eight levers, with four mounted at each side of the ram assembly.

Upper lever 30, as best seen in Figs. 4 and 7, is pivoted through a shaft 41 relatively to a bracket portion 42 forming part of the base member 15 of my invention. Lower lever 32 is pivoted through a shaft 43 to the same bracket 42 of the base member 15. Because of the particular arrangement, the offset relationship of the levers 30-32 previously stressed is useful also in more rigidly mounting the levers 30-32 relatively to the main frame 15. Of course, the levers at the opposite side of the ram assembly 17 will be similarly pivoted to a bracket 42a as need not here be emphasized.

Levers 29 and 31 at the right side of the ram assembly pictured in Fig. 4 are pivoted to brackets 45, 45a forming integral parts of what I term an actuator A. This actuator A may be fabricated in any desired manner, one particular form of fabrication being that illustrated best in my drawings and especially in Figs. 7, 8 and 9. Naturally, the levers 29 and 31 will form a fairly rigid connection between the ram assembly 17 and the actuator because of the particular offset relation that has already been referred to. It is now quite obvious that when the ram piston 20 is moved relatively to the ram cylinder 18 from its full line position of Fig. 1 to the full line position of Fig. 4 and then to its dash and dotted line position of Fig. 1, the racks 24 will effect movement of the eight levers comprising levers 29-32. These levers will move from the full line position of Fig. 1 to the dash and dotted line position of Fig. 1 and the position illustrated in Fig. 7. Because of the parallelogram relationship between the several levers and the main frame of the truck on the one side and the load actuator A on the other side, the load actuator will be extended a considerable distance away from the main frame of the truck. Upon opposed movement of the ram piston 20, the actuator will, of course, be brought into very close coupled relation to the truck.

As is quite apparent from Figs. 1 and 2, when the load actuator is brought closely to the main frame of the truck, my entire assembly including the load actuator occupies but very little space. Therefore, the overall length of the truck is not substantially increased. Similarly, as is particularly well seen in Fig. 2, the width of my attachment is considerably less than the width of the truck so that my attachment does not increase the overall width of the truck as is the case in many prior art constructions.

The load actuator A has formed thereon a gripper plate 46 extending for the full width of the actuator. This gripper plate is preferably made quite rigid and is welded to the brackets 45, 45a and the actuator. In addition, the plate 46 is so formed that its lower surface 46a will lie in juxtaposed relation to the upper surface 47 of a pair of forks 48 extending from and forming a part of the carriage 13 of my invention. Of course, the forks 48 could conceivably be secured to the base member 15 of my attachment, but I prefer to apply the forks directly to plate 13a just as member 15 is applied to plate 13a. In either case, it is important merely to know that I do prefer to use forks or a platform cooperating with the load actuator A, and that these forks or the platform may be a part of the truck or part of my attachment, the operation being the same regardless of the particular relationship of the

parts. It is now apparent, however, that during the linear movement of the actuator from the full line position of Fig. 1 to the dash and dotted line position of Fig. 1, the gripper plate 46 will lie in juxtaposed relation to the upper surfaces 47 of the forks 48.

Extending from the actuator A is a pair of upper brackets 49, there being pivoted to each bracket 49 at 50, a ram cylinder 51 of what I term a gripper ram. Within each ram cylinder 51 there is mounted a ram piston 52 equipped with a piston head 53. A spring 54 presses at one end against each piston head 53 and at its other end against a washer 55 carried by a closing block 56 that closes the lower end of each ram cylinder 51. The lower ends of the two ram pistons 52 are secured to a gripper bar 57 adapted to coact with the gripper plate 46. Gripper bar 57 has at its lower end a rubber part 58 adapted to ride toward a groove 59 in the gripper plate 46 so as to grip a paper or thin metal plate 60 as well illustrated in Figs. 9 and 10. Gripper bar 57 has a series of brackets 61 whereby to be pivoted to a series of levers 62 that are in turn pivoted at 63 to the main frame of the actuator A. In this manner, the movement of the gripper bar 57 is controlled between an upper position of the gripper bar illustrated in Fig. 9, and a lower gripping position illustrated in Fig. 10. It will be further appreciated that the gripper bar 57 will move from the position of Fig. 9 to the position of Fig. 10 upon movement of the pistons 52 by the introduction of hydraulic fluid into the ram cylinders 51. It will be further understood that this movement will be in opposition to the two springs 54 of the two rams and that when the application of fluid to the piston heads 53 stops, the springs 54 would immediately act to return the gripper bar to the position of Fig. 9.

It will be recalled that in Fig. 5 the shaft 34 was described as mounted within a bearing sleeve 35 carried by the ram assembly 17. As a very important feature of my invention, I make it possible to adjust each of the shafts 34 relatively to the ram assembly 17, and thus am able to compensate for any errors in the fabrication of my assembly, the several levers, and all the other operating parts thereof that I have described. I am able to obtain this adjustment of the shafts 34 by forming each of the sleeves 35 so that its bearing relatively to the assembly 17 is eccentric with regard to the axis of the shaft 34. The particular sleeve 35 to which I have alluded is shown in Fig. 6, and as there seen is formed with a flange 64 that is castellated as at 65 for coaction with a wrench. A locking lug 66 held by a screw 67 is adapted to coact with the castellations 65 to hold the flange 64 and the bearing sleeve 35 in any position to which it may be rotated by a wrench applied thereto. It is therefore seen that merely by removing the locking lug 66, the sleeve 35 may be rotated into a particular adjusted position and then locked in that position. As will be seen in Fig. 5, each of the four bearing sleeves there illustrated is formed in exactly the same manner as the bearing sleeve just described, and is similarly held locked in any adjusted position to which it may be moved.

Referring now to Fig. 12, I show a schematic view of the several parts of my invention whereby the push pull ram assembly and the gripper rams are operated. It will be noted that I employ a reservoir 68 in communication with a gear pump 69 that is driven by a motor 70. Preferably all these parts are carried by base member 15 of my 75 gear pump 69. Therefore, the actuator will re-

attachment so that the entire attachment may readily be applied as an operating unit to a truck. The pump 69 moves fluid from the reservoir past the check valve 71 and through pipe 73 to a selector valve having a rotating valve body 79 equipped with passages 80, 81. The selector valve has for communication with the passages 80, 81, passages 82, 83, 84, and 85. Passage 83 communicates with a pipe 86 that leads to the upper end of the push-pull ram cylinder 18 as is not only shown in Fig. 12, but may also be seen in Fig. 5. Passage 84 leads to a pipe 87 that is in communication with the reservoir. Passage 85 leads to a pipe 88 that connects with a pipe 89 leading to the upper ends of the two gripper ram cylinders 51. Pipe 83 continues also into a sequence valve where it is in communication with a passage 90 and a passage 91. Passage 91 is in communication past ball valve 92 with a passage 93 leading to pipe 94. Pipe 94 goes to the lower end of the push-pull ram cylinder 18. Passage 90 leads past a valve 95 to a passage 96 in communication with pipe 94 and the lower end of the push pull ram cylinder 18.

25 In the position of the parts shown in Fig. 12, the selector valve has been actuated so that its rotating body 79 is in a pull-grip position calling for a gripping of the load and a pulling of the load actuator A from its dash and dotted line position of Fig. 1 to its full line position of the same figure. Let us now consider just how the fluid flows. First, the gear pump will be actuated by the closing of the motor circuit to bring fluid from the reservoir past the check valve 71 and into pipe 73. The fluid will then flow through passage 82, passage 86, passage 85, and pipe 83 toward the sequence valve. The fluid cannot, of course, flow past the ball valve 92, but it will flow towards the valve 95. The setting of the valve 95 is such that considerable pressure will be required to unseat the valve. Therefore, the fluid will first flow through pipe 89 toward the two gripper ram cylinders 51. The pistons 52 of the gripper rams will be actuated and will move downwardly against the force exerted by springs 54, thereby bringing the gripper bar 57 downwardly to its position of Fig. 10 so as to grip a paper 60 on which a load may have been placed. As soon as the gripper rams have thus been actuated, 45 pressure will build up in the system until the valve 95 of the sequence valve body will be unseated. Fluid will now flow through passages 90, 96 into pipe 94 to the lower end of the push pull ram cylinder 18. The ram 20 will now move upwardly from its dash and dotted line position of Fig. 1 to its position of Fig. 4, and then will continue to its solid line position of Fig. 1. The fluid on the upper side of the ram piston 20 will move through pipe 86 and thence through passages 83, 55 84 to pipe 87 and back to the reservoir 68.

When the uppermost position of the push-pull ram piston 20 is reached, the selector valve body 79 will be rotated to a hold position. This stops the motor and brings passage 80 into communication with passages 84, 85. At the same time, 65 passage 81 will be brought into communication with passages 82 and 83. With the parts in this position, fluid will no longer flow toward the push-pull ram. However, the push-pull ram will not move downwardly because no fluid can flow from its lower end because of the seating of the ball valve 92 in a particular position. Fluid cannot move from the other side of the push-pull ram because of the presence of check valve 71 and gear pump 69. Therefore, the actuator will re-

main in the particular position to which it has been moved, and this is a particular feature of my invention that I believe to be of considerable importance. At the same time, however, fluid will flow from above the gripper rams as the gripper rams are moved upwardly by springs 54. Thus, the fluid will flow through pipe 89, pipe 88, passage 85, passage 80, passage 84, pipe 87, and to reservoir 68. Because of this arrangement, it is apparent that immediately upon the stoppage of the pulling movement of the load actuator, the gripper bar 57 will release the paper or other type sheet on which a load has been placed.

Let us now consider that in the full line position of the parts in Fig. 1 a load rests on the forks 48 and on the upper surface of the said forks and that it is desired to push the load off the forks. Selector valve is now rotated to push position to bring passage 80 in communication with passages 82, 83 and passage 81 in communication with passages 84, 85, while the motor 70 is simultaneously started. Fluid will now flow from the reservoir 68 through gear pump 69 past check valve 71 into pipe 78. From the pipe 78 fluid will flow through passage 82, passage 80 and to passage 83 to pipe 86 and the upper end of the ram cylinder 18. This will effect a downward movement of the ram piston 20 from its full line position of Fig. 1 to its dash and dotted line position of Fig. 1. This movement of the ram piston 20 will, of course, effect movement of the actuator from its solid line position of Fig. 1 to its dash and dotted line position of the same figures and the load will be moved off the forks 48. At the same time, fluid will flow from below the ram piston 20 through pipe 94 with the pressure sufficient to unseat ball valve 92. Fluid will continue to flow through pipe 88 into passage 85 and thence through passages 84, 81, 85 into pipe 87 and back to the reservoir. It will be noted that no fluid will flow to the gripper ram cylinders 51. Therefore, when the selector valve is operated in this last manner, the push-pull ram alone will be operated and the load will be moved, but there will be no actuation of the gripper bar 57. It will be well to emphasize that the controls thus described are purely schematic and that many arrangements of valves and other means can readily be conceived for yielding the type of control I have contributed here.

I believe that the operation of my invention as earlier outlined will now be understood by those skilled in the art, and that its considerable contribution will be fully appreciated.

I now claim:

1. In a truck of the class described, a frame, a ram assembly, a load actuator, a ram piston in said ram assembly movable relatively thereto, upper and lower levers pivoted at one end thereof to one side of said ram assembly, the other ends of said levers being pivoted to said frame so as to form a parallelogram arrangement of said levers and said frame and ram assembly, upper and lower levers similarly extending between the other side of said ram assembly and said load actuator and similarly secured thereto, and means whereby said ram piston applies force directly to each of the four ends of said four levers pivoted to said ram assembly for swinging said four levers on their pivots to move said load actuator toward and away from said frame.

2. In a truck of the class described, a frame, a load actuator, a ram assembly positioned in spaced relation to said frame and load actuator, a ram piston in said ram assembly movable relatively thereto, upper and lower levers pivoted at

one end thereof to one side of said ram assembly, the other ends of said levers being pivoted to said frame so as to form a parallelogram arrangement of said levers and said frame and ram assembly, upper and lower levers similarly extending between the other side of said ram assembly and said load actuator and similarly secured thereto, rack means movable by said ram piston, and gear means whereby said rack means moves directly each of said four levers on their pivots to move said load actuator toward and away from said frame.

3. In a truck of the class described, a frame, a ram assembly, a load actuator, a ram piston in said ram assembly movable relatively thereto, upper and lower levers pivoted at one end thereof to one side of said ram assembly, the other ends of said levers being pivoted to said frame so as to form a parallelogram arrangement of said levers and said frame and ram assembly, upper and lower levers similarly extending between the other side of said ram assembly and said load actuator and similarly secured thereto, a gear sector secured to each of said four levers, and a two-faced rack positioned between the gear sectors of the levers for actuating all four of said levers simultaneously to move said load actuator toward and away from said frame.

4. In a truck of the class described, a frame, a ram assembly, a load actuator, a ram piston in said ram assembly movable relatively thereto, upper and lower levers pivoted at one end thereof to one side of said ram assembly, the other ends of said levers being pivoted to said frame so as to form a parallelogram arrangement of said levers and said frame and ram assembly, upper and lower levers similarly extending between the other side of said ram assembly and said load actuator and similarly secured thereto, gear sectors secured to each of said four levers coaxially with the pivots of said lever to said ram assembly, and a two-faced rack positioned between the four gear sectors of the levers for actuating all four of said levers simultaneously to move said load actuator toward and away from said frame.

5. In a truck of the class described, a frame, a ram assembly, a load actuator, a ram piston in said ram assembly movable relatively thereto, upper and lower levers pivoted at one end thereof to one side of said ram assembly, the other ends of said levers being pivoted to said frame so as to form a parallelogram arrangement of said levers and said frame and ram assembly, upper and lower levers similarly extending between the other side of said ram assembly and said load actuator and similarly secured thereto, gear sectors secured to said several levers, and a two-faced rack positioned between the gear sectors of the levers for actuating all said levers simultaneously to move said load actuator toward and away from said frame, said upper and lower levers at each side being laterally offset relatively to one another so that the longitudinal axes of said levers move into coincidence to bring said load actuator and main frame into the closest possible relationship.

6. In a truck of the class described, a frame, a ram assembly, a load actuator, a ram piston in said ram assembly movable relatively thereto, upper and lower levers pivoted at one end thereof to one side of said ram assembly, the other ends of said levers being pivoted to said frame so as to form a parallelogram arrangement of said levers and said frame and ram assembly, upper and lower levers similarly extending between

the other side of said ram assembly and said load actuator and similarly secured thereto, and means whereby said ram piston applies force directly to each of the four ends of said four levers pivoted to said ram assembly for swinging said four levers on their pivots to move said load actuator toward and away from said frame, said upper and lower levers at each side being laterally offset relatively to one another so that the longitudinal axes of said levers move into coincidence to bring said load actuator and frame into the closest possible relationship.

7. In a truck of the class described, a frame, a ram assembly, a load actuator, a ram piston in said ram assembly movable relatively thereto, upper and lower levers pivoted at one end thereof to one side of said ram assembly, the other ends of said levers being pivoted to said frame so as to form a parallelogram arrangement of said levers and said frame and ram assembly, upper and lower levers similarly extending between the other side of said ram assembly and said load actuator and similarly secured thereto, means whereby said ram piston moves said levers on their pivots to move said load actuator toward and away from said frame, and eccentric sleeve bearings for at least certain of said pivots of said levers.

8. In a truck of the class described, a load actuator, a ram cylinder and a ram piston for pushing and pulling said load actuator relatively to said truck, a source of fluid pressure, valve means set for holding said piston and cylinder against relative movement except upon application of fluid under pressure between said ram piston and ram cylinder from said source of fluid pressure, a gripper movably mounted on said load actuator, hydraulic means for moving said gripper relatively to a part of said actuator whereby to grip a part of the load between said gripper and said actuator, means whereby fluid under pressure is directed solely to one end of said ram cylinder to move said actuator to push a load, means whereby fluid under pressure is supplied to the other end of said ram cylinder to move said actuator to pull the load, means whereby fluid under pressure is first supplied to said hydraulic means in advance of said other end of said cylinder whereby the load is first gripped and then pulled, a spring pressing said gripper away from gripping position, and means releasing the fluid in said hydraulic means upon the stoppage of the flow of fluid under pressure to said hydraulic means whereby said spring moves said gripper to release the load while said load actuator will be held in the position to which it was moved by the application of fluid under pressure to said piston and cylinder.

9. In a truck of the class described, a load actuator, a ram cylinder and a ram piston for pushing and pulling said load actuator relatively to said truck, a source of fluid pressure, means for holding said piston and cylinder against relative movement except upon application of fluid under pressure between said ram piston and ram cylinder from said source of fluid pressure, a gripper movably mounted on said load actuator, hydraulic means for moving said gripper relatively to a part of said actuator whereby to grip a part of the load between said gripper and said actuator, means whereby fluid under pressure is directed solely to one end of said ram cylinder to move said actuator to push a load, means whereby fluid under pressure is supplied to the other end of said ram cylinder to move said

actuator to pull the load, means whereby fluid under pressure is first supplied to said hydraulic means in advance of said other end of said cylinder whereby the load is first gripped and then pulled, and a spring pressing said gripper away from gripping position whereby upon the stoppage of the flow of fluid under pressure to said hydraulic means said gripper will release the load while said load actuator will be held in the position to which it was moved by the application of fluid under pressure to said piston and cylinder.

10. In a truck of the class described, a load actuator, a ram cylinder and a ram piston for pushing and pulling said load actuator relatively to said truck, a source of fluid pressure, valve means set for holding said piston and cylinder against relative movement except upon application of fluid under pressure between said ram piston and ram cylinder from said source of fluid pressure, a gripper movably mounted on said load actuator, hydraulic means for moving said gripper relatively to a part of said actuator whereby to grip a part of the load between said gripper and said actuator, selector means whereby fluid under pressure is directed solely to one end of said ram cylinder to move said actuator to push a load upon the setting of said selector means in one position, the setting of said selector means in another position directing fluid under pressure from said source to said hydraulic means and also to the other end of said ram cylinder, and sequence means whereby said fluid under pressure first actuates said hydraulic means to grip the load and then actuates said ram and cylinder to pull the load.

11. In a truck of the class described, a load actuator, a ram cylinder and a ram piston for pushing and pulling said load actuator relatively to said truck, a source of fluid pressure, valve means set for holding said piston and cylinder against relative movement except upon application of fluid under pressure between said ram piston and ram cylinder from said source of fluid pressure, a gripper movably mounted on said load actuator, hydraulic means for moving said gripper relatively to a part of said actuator whereby to grip a part of the load between said gripper and said actuator, selector means whereby fluid under pressure is directed solely to one end of said ram cylinder to move said actuator to push a load upon the setting of said selector means in one position, the setting of said selector means in another position directing fluid under pressure from said source to said hydraulic means and also to the other end of said ram cylinder, sequence means whereby said fluid under pressure first actuates said hydraulic means to grip the load and then actuates said ram and cylinder to pull the load, and a spring pressing said gripper away from gripping position whereby upon the stoppage of the flow of fluid under pressure to said hydraulic means said gripper will release the load while said load actuator will be held in the position to which it was moved by the application of fluid under pressure to said piston and cylinder.

12. In a truck of the class described, load supporting and raising means, load moving means carried by said load supporting and raising means, clamping means carried by said load moving means, hydraulic means for actuating said clamping means to clamp a part of a load, a ram for moving said load moving means relatively to the load supporting and raising means, a source of fluid pressure, a manually operated valve, means

through which said valve when in one position directs fluid pressure toward said hydraulic means and said ram, and a second valve automatically directing the fluid pressure first to said hydraulic means and then to said ram.

13. In a truck of the class described, forwardly projecting load supporting and raising means, pusher means carried by said load supporting and raising means, clamping means carried by said pusher means, hydraulic means for actuating said clamping means to clamp a part of a load, a ram for moving said pusher means forwardly and rearwardly relatively to the load supporting and raising means, a source of fluid pressure, a manually operated valve, means through which said valve when in one position directs fluid pressure simultaneously toward said hydraulic means and said ram, and a second valve automatically directing the fluid pressure first to said hydraulic means to effect actuation of the clamping means and then to said ram whereby to effect rearward movement of the pusher means and load subsequently to clamping of the load.

14. In a truck of the class described, forwardly projecting load supporting and raising means, vertical pusher means carried by said load supporting and raising means, clamping means carried by said pusher means adjacent to the load supporting surface of said load supporting means, hydraulic means for actuating said clamping means to clamp a part of a load, a ram for moving said pusher means forwardly and rearwardly relatively to the load supporting and raising means, a source of fluid pressure, a first valve, means through which said valve when in one position directs fluid pressure simultaneously toward said hydraulic means and said ram, said hydraulic means being in direct unobstructed communication with said first valve, a further valve interposed between said ram and said first valve for preventing the flow of fluid to said ram, and means forming a part of said further valve and responsive to the pressure developed between said hydraulic means and said first valve to effect a flow of fluid to said ram.

15. In a truck of the class described, forwardly projecting load supporting and raising means, vertical pusher means carried by said load supporting and raising means, clamping means carried by said pusher means adjacent to the load supporting surface of said load supporting means, hydraulic means for actuating said clamping means to clamp a part of a load, a ram for moving said pusher means forwardly and rearwardly relatively to the load supporting and raising means, a source of fluid pressure, a manually operated valve, means through which said valve when in one position directs fluid pressure toward said hydraulic means and said ram, a second valve automatically effecting the flow of fluid first to said hydraulic means until development of predetermined fluid pressure incidental to actuation of the clamping means, and then to one end of said ram, whereby to effect clamping of the load and rearward movement of the pusher means and load, and means through which said manually operated valve when in a second position directs fluid pressure to the opposed end of said ram to move the pusher means forwardly relatively to the load supporting and raising means while simultaneously effecting the exhaust of fluid from said hydraulic means.

16. In a truck of the class described, forwardly projecting load supporting and raising means, pusher means carried by said load supporting

and raising means, clamping means carried by said pusher means, hydraulic means for actuating said clamping means to clamp a part of a load, a ram for moving said pusher means forwardly and rearwardly relatively to the load supporting and raising means, a source of fluid pressure, a manually operated valve, means through which said valve when in one position directs fluid pressure simultaneously toward said hydraulic means and said ram, a second valve automatically effecting the flow of fluid first to said hydraulic means to effect actuation of the clamping means, and then to one end of said ram whereby to effect rearward movement of the pusher means and load, and means through which said manually operated valve when in a second position directs fluid pressure to the opposed end of said ram to move the pusher means forwardly relatively to the load supporting and raising means while simultaneously effecting the exhaust of fluid from said hydraulic means.

17. In a truck of the class described, load supporting and raising means, pusher means carried by said load supporting and raising means, clamping means carried by said pusher means, hydraulic means for actuating said clamping means to clamp a part of a load, a ram for moving said pusher means forwardly and rearwardly relatively to the load supporting and raising means, a source of fluid pressure, a first valve, means through which said valve when in one position directs fluid pressure toward said hydraulic means and simultaneously toward one end of said ram, a second valve automatically effecting the flow of fluid first to said hydraulic means to clamp the load, and then to the said end of the ram upon development of predetermined fluid pressure incidental to actuation of the clamping means whereby to move the pusher means and load rearwardly, means through which said first valve when in a second position directs fluid pressure to the opposed end of said ram to move said pusher means forwardly, springs pressing said clamping means toward release position, and said first valve in its second position effecting the exhaust of fluid from said hydraulic means under the pressure of the springs on said clamping means.

BRONISLAUS I. ULINSKI.
